UNITED STATES PATENT OFFICE.

SYDNEY W. REYNOLDS, OF RIPON, CALIFORNIA.

SPECTACLE-CASE CLIP.

1,411,065.

Specification of Letters Patent. Patented Mar. 28, 1922.

Application filed May 31, 1921. Serial No. 473,729.

To all whom it may concern:

Be it known that I, SYDNEY W. REYNOLDS, a citizen of the United States, residing at Ripon, county of San Joaquin, State 5 of California, have invented certain new and useful Improvements in Spectacle-Case Clips; and I do declare the following to be a full, clear, and exact description of the same, reference being had to the accompanying drawings and to the characters of reference marked thereon, which form a part of this application.

This invention relates to a holding clip for spectacle or eye-glass cases, the principal object of the invention being to provide a clip, which will be a permanent part of the case, and which will function to prevent the case from falling out of the wearer's pocket and possibly breaking the expensive 10 glasses therein.

The majority of men who do not have to wear their glasses continually prefer to carry their glass-cases in their vest pockets, which however are usually of insufficient 15 depth to completely receive the same. Therefore, under present conditions, whenever the person so carrying the case bends over to any extent, or moves the body violently in any manner, such as when running or jumping, the spectacle case is very 20 apt to be forced or jump out of the pocket, resulting, as previously stated, in the possible breakage of the glasses, or the loss of the same through the owner failing to notice their absence.

This tendency to leave the pocket is aided by the almost universal slick or glazed covering provided on the cases, as well as by the similar properties of the lining of the 25 pocket.

With my improved clip, the case is firmly held in place in the pocket, regardless of the extent it normally projects from the pocket, or of the smoothness of the exterior 30 surface of the case.

A further object of the invention is to produce a simple and inexpensive device, and yet one which will be exceedingly effective for the purposes which it is designed.

These objects I accomplish by means of such structure and relative arrangement of parts as will fully appear by a perusal of the following specification and claims.

In the drawings similar characters of

reference indicate corresponding parts in the several views.

Fig. 1 is a fanciful outline of the clothed bust of a man, showing a spectacle case as provided with my improved clip and carried in a vest pocket.

Fig. 2 is an edge view, enlarged, of the clip, showing one method of attaching it to the case.

Fig. 3 is a similar view, showing another manner of attachment of the clip.

Referring now more particularly to the characters of reference on the drawings, the numeral 1 denotes the spectacle case, of which the cover 2 is usually considered the front face, said face, as well as the entire 70 case, being usually of metal 3 covered with imitation leather 4 or similar material and lined with velvet 5.

My improved clip consists of a flat and relatively broad spring-metal strip 6, having connection with the case 1 or cover 2 a certain distance from one end, and depending free of said case toward the other end for a certain distance, the portion 6 being spaced slightly from the case throughout its extent. The lower or free end of this strip is preferably cupped toward the surface of the case as at 7 so as to firmly grip the goods of the pocket 8 in which the case may be placed, and yet will not tend 80 to catch in and tear the cloth.

The clip is intended to be permanently attached to the case or cover, which may be done in either of the following ways; and preferably during the manufacture of 90 the case.

Referring to Fig. 2, the clip 6 may have an extension 9 bent nearly parallel thereto, and projecting through a slit in the case metal 3, then lying between the said metal 95 and the lining 5. This extension may be soldered or otherwise rigidly fixed to the metal if desired.

Another method of attachment is shown in Fig. 3, the upper end of the clip having a short length 10 adapted to lie against the outside of the metal 3 between the same and the covering 4, and to be then soldered or riveted to the said metal.

Since the portion 6 is always practically 105 in sight, it is preferably made as neat appearing as possible, and may be nickel, silver or gold plated, or fancifully engraved,

depending on the taste and financial circumstances of the purchaser.

From the foregoing description it will be readily seen that I have produced such 5 a device as substantially fulfills the objects of the invention as set forth herein.

While this specification sets forth in detail the present and preferred construction of the device, still in practice such deviations from such detail may be resorted to 10 as do not form a departure from the spirit of the invention, as defined by the appended claims.

Having thus described my invention, what I claim as new and useful and desire 15 to secure by Letters Patent is:—

The combination with a spectacle case, of a spring clip projecting downwardly on the outside and spaced slightly therefrom, and an extension projecting from the 20 upper end of the clip and secured to the case, the latter having a covering material enveloping said extension.

In testimony whereof I affix my signature.

SYDNEY W. REYNOLDS.
